217,872

COMBINED DISPENSER BASE AND MOUNTING BRACKET

Marc H. Sessions, Los Angeles, Calif., assignor to Steiner
Company, a division of Steiner American Corporation,
Chicago, Ill., a corporation of Nevada

Filed Mar. 24, 1969, Ser. No. 16,398

Term of patent 14 years

Int. Cl. D6—01

U.S. Cl. D33—30

FIG. 1 is a perspective view of a combined dispenser base and mounting bracket showing my new design;

FIG. 2 is a top plan view thereof;

FIG. 3 is a side elevation thereof;

FIG. 4 is a front elevation thereof; and

FIG. 5 is a bottom plan view thereof.

The broken line representation of a container in FIGS. 1 and 2 is for purposes of illustration only.

I claim:

The ornamental design for a combined dispenser base and mounting bracket, as shown and described.
